GASEOUS DISCHARGE LAMP CIRCUIT

Donald Frederick Chapman, London, England, assignor to Thorn Electrical Industries Limited, London, England

Filed Sept. 24, 1959, Ser. No. 842,149

Claims priority, application Great Britain Sept. 26, 1958

3 Claims. (Cl. 315—98)

This invention relates to circuits for starting and operating one or more gaseous discharge devices, such as fluorescent lamps, from an alternating current supply, such lamps being provided with heatable electrodes, usually filamentary electrodes, at each end.

It is known that the voltage required to start such lamps is much higher than the voltage required for operation. To reduce starting voltage it is well known to provide initial preheating for the lamp electrodes, such preheating causing emission of electrons and ionisation of the gas filling and mercury vapour and thereby assisting starting. When the lamp has started it may be desirable to reduce or cut off the preheating current supplied to the lamp electrodes in order to reduce power losses and improve the life of the electrodes.

Known circuits have used a transformer with primary and secondary windings to provide a power supply to preheat the electrodes. In the "Quickstart" circuit, for example, the primary winding is connected between opposite ends of the lamp and two secondary windings are connected across the two electrodes respectively. With this circuit a choke ballast is used in series with the supply to ensure stability and limitation of lamp discharge current, and a capacitor is often connected across the supply to improve the low power factor introduced by the choke.

With such a circuit it has been found that lamp starting may be difficult if the ambient temperature is low or if atmospheric humidity is high. To overcome these starting difficulties it has been proposed to use low gas filling pressures inside the lamps and to coat the glass lamp surface with water-repellent materials. Such modifications to the lamp may increase cost and reduce life.

It is the object of the present invention to provide an improved circuit for starting and operating gaseous discharge lamps in which starting difficulties are reduced.

According to the present invention there is provided a circuit for starting and operating one or more gaseous discharge devices having heated electrodes from an alternating current supply, comprising a voltage step-down transformer having a primary winding and at least two secondary windings, the primary winding being connected in series with a ballast choke between supply terminals, two heater current terminals for connection to one lamp electrode being connected in series with one of the secondary windings and a capacitor between the supply terminals, and another of the secondary windings being connected to two further heater current terminals for connection to another lamp electrode.

The invention will be described, by way of example, with reference to the accompanying drawing containing circuit diagrams of a number of embodiments of the invention.

In FIG. 1 there is shown a fluorescent lamp F having filamentary electrodes A and B and an auto-transformer having terminals and taps 1, 2, 3 and 4. The parts 1—2 and 3—4 of the auto-transformer constitute secondary windings while the part 2—3 constitutes the primary winding. A ballast choke G is connected in series between the tap 3 and a supply terminal L. The electrode A is connected in series with the secondary winding 1—2 and a capacitor C between supply terminals N and L. The

2

electrode B is connected in parallel with the winding 3—4.

When a main switch (not shown) connecting the terminals N and L to an A.C. supply is closed, a momentary inrush of current occurs through the series circuit comprising capacitor C, winding 1—2, and lamp electrode A. This surge of current occurs because the capacitor is initially discharged and the surge persists for only a few microseconds until the capacitor becomes fully charged. The magnitude of the current surge which occurs when the circuit is switched on depends upon a number of factors including the value of the impedance presented by the winding 1—2 in series with the capacitor C. The current surge may be as much as 1000 amps. peak in a circuit such as that of FIG. 1 when connected to a 240 volt 50 cycle A.C. supply.

The momentary surge of current induces a momentary high voltage across the winding 1—2. Since the windings 2—3 and 3—4 are electromagnetically coupled to the winding 1—2 by transformer action, high instantaneous voltages are induced in the former. Because the winding 2—3 has many more turns than the winding 1—2, the voltage across 2—3 is many times that across 1—2. The result is that a very high transient voltage is induced across the winding 2—3, and hence between the end of the lamp, by the surge of current which occurs when the circuit is switched on. Such a high voltage, which may approach 2000 volts, although it does not start the main discharge in the lamp because at this time the filaments A and B are cold, serves to ionise the gas and vapour in the discharge space of the lamp and enables the main discharge to start at a lower voltage when the filaments have heated up.

After the initial inrush of current, conditions become steady, and the electrode A is heated by current flowing through the winding 1—2 while the electrode B is heated by a current from the winding 3—4. This latter secondary winding is energised by the voltage of the primary winding 2—3 which is almost equal to the supply voltage since the voltage drop across the choke G at this time before the main discharge has started is low.

The two electrodes A and B now rapidly reach a high temperature and emission of electrons occurs to help ionise the gas and vapour still further. When ionisation is sufficient the lamp will start and a heavy current then flows through the discharge space between the electrodes. This current is limited by the impedance of the choke G and a voltage drop now occurs across this choke. Voltage between the ends of the lamp is thus reduced after starting and since the primary winding 2—3 is also connected across the lamp the voltage on the winding 2—3 also drops.

In practical circuits the supply voltage is arranged to be about twice the voltage across the lamp during operation. Thus voltage on the winding 2—3 drops by about half after the lamp has started. Since the winding 3—4 is coupled to the winding 2—3, the voltage supplied to the electrode B drops after the lamp has started, thereby reducing the current and hence the power losses in this electrode.

When the lamp is operating, current through the electrode A is the vector sum of two antiphase components, i.e. the current through the capacitive branch and the current through the inductively controlled discharge path. Since these currents are anti-phase they tend to cancel each other, with the result that after the lamp has started the current through electrode A drops because of this partial cancellation as well as through the reduction of voltage of the primary winding 2—3.

During normal operation of the circuit of FIG. 1, the capacitor C serves to improve the power factor. Voltage across the capacitor C after the lamp has started can be

shown to be the vector sum of three voltages, namely the supply voltage, the voltage across the winding 1-2, and the voltage drop across the electrode A, and this capacitor voltage is found to be approximately equal to the supply voltage.

By way of example, in one circuit as shown in FIG. 1 the lamp F was a 5 ft. 80 watt, type MCF/U. The capacitor C was of 7.5 microfarads and the choke G an impedance of 210 ohms at 0.85 amp., 50 c./s. The primary winding 2-3 was of 1900 turns 38 SWG enamelled copper wire, each secondary winding was of 135 turns 26 SWG enamelled copper wire, and the core was a $27\frac{1}{2}2$ " stack of No. 182.N laminations punched from dynamo iron 0.32" thick. The supply was 230 volts, 50 c./s.

The following values were obtained after switching on and before the lamp started and after the lamp had started:

	Before starting	After starting
Transient peak volts across lamp	1,700	
Volts on electrode A	8.5	3.0
Volts on electrode B	10.5	5.0
Volts across capacitor C	243	230
Steady volts across lamp F	245	116
Supply current (amps.)	0.435	
Supply power (watts)	98	
Power factor		0.88 lagging

The circuits of FIGS. 2 to 5 differ only in minor respects from that of FIG. 1. Thus the connections of the electrode A and the capacitor C to the winding 1-2 are rearranged and the choke G is connected to tap 4 instead of to tap 3. The mode of operation is substantially the same as with FIG. 1. In FIG. 5 the choke G₁ is shown as having tappings in order to permit operation on different supply voltages. Moreover a resistor R is shown connected in parallel with the capacitor C in order to ensure rapid discharge of the capacitor when the circuit is switched off. A tapped choke G₁ and a resistor R may, of course, be used in any of the circuits.

In FIG. 6 the only change from FIG. 1 is that the choke G in FIG. 6 is connected to a further tap 5. This enables the steady voltage across the lamp during starting to be made substantially greater than the supply voltage. Such a circuit is, for example, suitable for use with an 8 ft. 125 watt fluorescent lamp which requires approximately 350 volts for satisfactory starting.

In FIG. 7 the transformer winding is extended beyond the point 4 to a point 6 to which the supply terminal L

is connected through the choke G. This enables the steady voltage across the lamp during starting to be reduced considerably below the supply voltage. This may be advantageous for short fluorescent lamps such as the 2 ft. 20 watt lamp which requires only about 110 volts for starting.

FIG. 8 shows how the circuit of FIG. 1 can be modified to operate two fluorescent lamps F₁ and F₂ in series. In FIG. 8 the filaments A₁ and B₂ of the lamps F₁ and F₂ respectively are supplied in the same way as the filaments A and B respectively in FIG. 1; the filaments B₁ and A₂ are supplied by a further secondary winding S on the transformer.

The other circuits can, of course, be similarly adapted to operate a plurality of lamps.

I claim:

1. A circuit for starting and operating at least one gaseous discharge device having heated electrodes from an alternating current supply, comprising a voltage step-down transformer having a primary winding and at least two secondary windings, a ballast choke, a capacitor, supply terminals for connection to a source of alternating current, first and second pairs of heater terminals each pair for connection to a lamp electrode, means connecting said primary winding in series with said ballast choke between said supply terminals, means connecting said first pair of heater terminals in series with one of said secondary windings and said capacitor between said supply terminals, and means connecting said second pair of heater terminals across another of said secondary windings, wherein said primary winding, said ballast choke, at least one of said secondary windings and said first pair of heater terminals are connected in series between said supply terminals, and means connecting at least one terminal of each pair of heater terminals to one of said alternating current supply terminals.

2. A circuit according to claim 1, wherein at least one of said secondary windings is constituted by a part of said primary winding.

3. A circuit according to claim 1, further comprising a resistor connected in parallel with said capacitor.
